UNITED STATES PATENT OFFICE.

EDWARD N. MAULL, OF CRESCENT CITY, FLORIDA, ASSIGNOR OF ONE-HALF TO JOHN W. MILLER, OF SAME PLACE.

FRUIT-SORTING MACHINE.

SPECIFICATION forming part of Letters Patent No. 673,127, dated April 30, 1901.

Application filed July 9, 1900. Serial No. 23,022. (No model.)

To all whom it may concern:

Be it known that I, EDWARD N. MAULL, a citizen of the United States, residing at Crescent City, in the county of Putnam and State of Florida, have invented a new and useful 5 Fruit-Sorting Machine, of which the following is a specification.

My invention is an improved fruit-sorting machine, its object being to provide a fruit- 10 sorter which is adapted to sort fruit according to size and to deliver the same without injury into spouts or receptacles for the different sizes of fruit.

My invention consists in the peculiar 15 construction and combination of devices herein-after fully set forth, and particularly pointed out in the claims.

In the accompanying drawings, Figure 1 is 20 a top plan view of a fruit-sorter embodying my improvements. Fig. 2 is a detail top plan view of the volute gage and its radially-adjustable sorting-arms. Fig. 3 is a vertical 25 central sectional view of my improved fruit-sorter, taken in line with the crank-shaft thereof. Fig 4 is a detail top plan view of the spider. Fig. 5 is a detail transverse sectional view through one side of the volute gage.

The supporting-base 1, which is adapted to 30 be secured on a floor, is provided with a vertical central opening 2, in which is the lower end of a supporting-standard 3, which is adapted to be adjusted vertically in the base and is secured at any desired adjustment by a set-screw 4. Near the upper end of the standard 35 is secured a spider 5 by means of a set-screw 6, which passes through one side of its hub and engages with the standard. Said spider is provided with a series of radial arms 40 7 of suitable length, and at the outer end of each of the said arms is formed a lug or ear 8, in which is a horizontal opening. The outer ends of one pair of said radial arms are connected together by a web 9, from which 45 extends a radial arm 9^a, provided on its upper side, at its outer and inner ends, with a pair of vertical standards 10, which form the bearings for the crank-shaft 11. As will be noted from the foregoing and by reference 50 to the drawings, this spider may be very

cheaply constructed of iron cast in a single piece.

A series of radially-adjustable supporting-arms 12 are secured in the openings in the lugs 8 of the spider-arms by means of pairs 55 of nuts 13, which are screwed on the threaded inner portions 14 of said supporting-arms 12, the said nuts bearing against opposite sides of said lugs of said spider-arms. The outer ends of the said supporting-arms 12 are up-turned vertically at 15, and secured to the said upturned ends of said series of supporting-arms is the curved gage 16, which is preferably of volute form, but which may be circular in form. Said gage is of iron, steel, or 60 other suitable material and has its inner side concave in form, as at 17.

18 represents a flexible guide, which is preferably made of rubber hose provided with an interior core 19, made of spirally-wound wire. 70 Said guide may, however, be an air-inflated tube or otherwise suitably constructed. The said flexible guide bears against the said gage, in the concave side thereof, and is of the same form as the said gage, and the latter is provided with a series of adjusting thumb-nuts 20, which operate in threaded openings in the gage and have their inner ends bearing against the outer sides of the said flexible guide. By means of this construction the said 75 guide may be adjusted at any point within the gage, and by means of the adjustable sorting-arms 12 the gage may be adjusted to any desired curved form from the spider.

In the upper end of the vertical standard 3 85 is screwed the lower end of a vertical axle or spindle 21, having the ball-bearings 22, in which is mounted a revoluble wheel 23, which, as here shown and preferably, is an ordinary bicycle-wheel provided with an air-inflated or 90 pneumatic tire 24. As will be observed by reference to Fig. 1, this wheel is mounted eccentrically within the curved gage and the runway formed between the tire of the wheel, and the opposing guide 18 widens progressively 95 in the direction of the arrow in Fig. 1 from the inner end 25 to the outer end 26 of said runway.

On the crank-shaft 11 is keyed a frictional wheel 27, which bears against the under side 100

of the tire of the wheel and is adapted to communicate rotary motion to said wheel when said shaft 11 is turned by its crank 28. The runway is divided into a series of ports 5 29 of progressively-greater width by the supporting-arms 12, and said supporting-arms are connected together in pairs by a series of cloth or other suitable spouts or receptacles 30, as shown, adapted to receive the fruit, 10 which is assorted in its passage through the runway, the smallest size fruit passing into the first of said receptacles or spouts, the next size fruit into the next of said receptacles or spouts, and so on throughout the series. 15

In the operation of my improved fruit-sorter the fruit is fed by any suitable device or by hand, as the case may be, to the inner end of the runway, and the rotation of the 20 inner wheel causes the fruit to be carried in said runway until it reaches a point where the width of the runway is greater than its own diameter, whereupon it falls into one of the spouts or receptacles.

25 By having the guide 18 flexible and providing it with means, as hereinbefore described, whereby it may be adjusted in the volute gage the shape of the outer side of the gage may be slightly modified to meet the requirements of varying conditions and adapt the machine to be used for assorting various kinds of fruit. The pneumatic tire 24 being flexible and yielding the same will yield slightly, as may be required to permit the 30 escape of the fruit when of other than spherical form or when irregular in shape from the runway without injury to such fruit. Furthermore, the said pneumatic tire 24 serves not only as an elastic surface for the inner 35 moving side of the runway, but also constitutes a yielding frictional surface for contact with the friction-wheel 27 on the crank-shaft.

40 A fruit-sorter thus constructed is exceedingly cheap and simple, is adapted to be operated by a very slight expenditure of power, is thoroughly efficient, is not likely to get out of order, and can be adjusted and adapted to sort various kinds of fruit.

Having thus described my invention, I 45 claim—

50 1. In a fruit-sorter, the combination of a relatively-fixed curved guide, a revoluble wheel arranged within said guide and eccen-

trically with relation thereto, said wheel and guide forming a runway between them, a 55 bearing for said wheel, and means to rotate said wheel, and means to support and adjust said curved guide, substantially as described.

2. A fruit-sorter having a curved gage and the revoluble wheel arranged eccentrically 60 with relation thereto, said wheel and gage forming a guide-runway between them, one of the sides of said guide-runway having an air-inflated yielding contacting surface, substantially as described. 65

3. In a fruit-sorter, the combination with the curved outer gage forming one side of the runway, of the wheel mounted eccentrically within said gage and having the air-inflated or elastic tire, said tire forming the inner side 70 of the runway, and the friction-wheel bearing against said tire and means to rotate said friction-wheel, substantially as described.

4. In a fruit-sorter, the combination with the inner revoluble wheel, of the volute-gage 75 frame without said wheel and having the adjustable guide on its inner side, for the purpose set forth, substantially as described.

5. In a fruit-sorter, the combination with the inner revoluble wheel, of the volute-gage 80 frame without said wheel and having the adjustable guide on its inner side, said guide comprising the elastic tube, substantially as described.

6. The combination, in a fruit-sorter, of the 85 standard, the spider, the adjusting-arms on said spider, the volute gage supported by the said arms, the inner wheel on said standard, and devices to rotate said wheel, substantially as described. 90

7. In a fruit-sorter, the combination of the inner revoluble wheel having the elastic tire, the curved elastic guide without and eccentric to said wheel, said wheel and guide forming a runway between them, and said guide 95 having the series of supporting-arms, and the series of flexible spouts or receptacles supported by said supporting-arms under said runway, substantially as described.

In testimony that I claim the foregoing as 100 my own I have hereto affixed my signature in the presence of two witnesses.

EDWARD N. MAULL.
